UNITED STATES PATENT OFFICE.

JAMES E. BALDWIN, OF EAST WILLISTON, NEW YORK, ASSIGNOR, BY MESNE ASSIGNMENTS, TO FULTON MANUFACTURING CO., OF ERIE, PENNSYLVANIA, A CORPORATION OF PENNSYLVANIA.

ELECTRIC IGNITION DEVICE.

1,050,418.

Specification of Letters Patent. Patented Jan. 14, 1913.

Application filed March 10, 1906. Serial No. 305,279.

To all whom it may concern:

Be it known that I, JAMES EDWARD BALDWIN, a citizen of the United States, residing at East Williston, Nassau county, and State 5 of New York, have invented certain new and useful Improvements in Electric Ignition Devices, of which the following is a specification.

My invention relates to hydro-carbon 10 motors of the two cycle type and is designed primarily to afford more effective control of the operation of such engines through the medium of the sparking mechanism and connections, and secondarily, to afford a motor 15 of this class which may be run with equal facility in either direction. Incidentally it involves the reversal of the direction of motion of the motor by means which are inherent, simple and automatic in action.

20 The invention consists essentially, in conjunction with variable sparking mechanism by which the sparking may be effected either during the advance or recession of the piston, of an eccentric and intermediate connections for operating said variable 25 sparking mechanism, said eccentric being mounted loosely, by preference, directly upon the crank shaft of the motor, and being formed with key seats 90° apart or approximately 30 so, with a free key space between them, the key upon the crank shaft coinciding in position with the radial center of the crank, substantially as hereinafter set forth.

In the accompanying drawings I illustrate 35 the embodiment of the essential features of my invention in a motor adapted for use in driving the shaft of a marine propeller, or other shaft designed to be rotatable in either direction, although I do not 40 restrict myself in this respect, since the main object is to effectually control and regulate the operation of the engine irrespective of the direction of rotation. It is also to be understood that I do not limit myself to a 45 motor of the vertical type.

Figure 1, is a front elevation of an upright engine of the marine type, with parts broken away and the cover of the variable 50 sparking mechanism removed; Fig. 2, is a central vertical sectional elevation of the motor taken on a plane of line at right angles to Fig. 1; Fig. 3, is a front view, upon an enlarged scale of the cover inclosing the contact mechanism by which "make

and break" sparking is controlled; Fig. 4 55 is a similar view with the cover partly broken away, illustrating the position of the parts at the point of "make" of contact; Fig. 5, a similar view illustrating the position of the parts at the point of "break" of 60 contact; Fig. 6, is a sectional view on plane of line 6—6 Fig. 3, certain parts being shown in elevation; Fig. 7, is a rear view of the sparker plug; Fig. 8, a top view of the same, partly in section; Fig. 9, is a section upon 65 plane of line 9—9 Fig. 8; Fig. 10, is a section of the body of the plug only, taken upon plane of line 10—10 Fig. 7. Fig. 11, is a sectional elevation upon plane of line 11—11 Fig. 8; Fig. 12, is an elevation in detail of 70 the sparking rock lever; Fig. 13, a diagrammatic view showing a general outline of the motor in front elevation and illustrating the use of "jump" spark mechanism and connections, in combination with my sparking 75 eccentric; Fig. 14, an elevation showing an alternative form of spark mechanism for "jump" sparking, the cover being omitted; Fig. 15, is a section upon plane of line 15—15 Fig. 14; Fig. 16, is a section upon 80 plane of line 16—16 Fig. 14.

In the drawings A represents the casing of the motor containing the piston cylinder A', and sealed crank chamber A² which communicates with the said piston cylinder 85 through the passage a. a', is the inlet port communicating with a suitable carburetor, and a², the exhaust port. The space a³, at the top of the cylinder A', constitutes the combustion chamber into which protrudes 90 the inner end of the sparker plug J. P is the piston connected by the pitman p, with the crank c, upon the driving shaft C, which is mounted in suitable bearings and carries a fly-wheel C', in the usual manner. In 95 fact the construction and operation of this type of motor is so well known that the matter need be referred to herein only in so far as may be necessary in illustrating the functions and operation of my new form of 100 eccentric E for actuating the sparking mechanism, it being understood of course that I do not limit myself to this particular form or type of hydro-carbon motor.

The distinguishing feature of my construction and operation of parts consists in the use of a special form of eccentric E upon the driving shaft by means of which 105

the sparking mechanism is actuated. As is well known the best results are attained in a hydro-carbon motor of this class by sparking or igniting the charge of hydrocarbon above the piston prior to the completion of the upward or compression stroke of the latter so that the full force of the explosion of the compressed charge is imparted to the piston just as it passes the upper 5 dead center,—the time between the sparking and the complete combustion of the charge being sufficient, practically, to admit of the completion of the advance stroke of the piston and compression of the charge. In 10 other words, by the time the advance stroke of the piston is completed the maximum pressure is attained, and is utilized to the fullest advantage during the receding movement of the piston. Under these conditions, 15 obviously, the lead of spark, whether fixed or adjustable, is operative only for a given direction of rotation of the crank shaft, and a reversal of direction of rotation would result in retarded sparking, or sparking 20 beyond the dead center after the receding movement of the piston had begun, thereby rendering less effective the force of the explosion, for reasons well known. This obstacle has been heretofore overcome by the 25 use of rotating timing devices and other extraneous appliances interposed between the crank shaft and the sparking mechanism, but such mechanical expedients necessarily involved complication and expense, and call 30 for the exercise of skilled labor in their manipulation,—all of these being objectionable features which I obviate or eliminate without resort to the use of additional or auxiliary parts or appliances. In other 35 words I produce a motor which may be operated and controlled in either direction with equal facility by forming my sparking eccentric E, with a key way e, which will admit of desirable lost motion equivalent 40 to 90° in either direction, or 45° on either side of the radial center of the crank with which the center of the key e', on the crank shaft coincides,—the sparking eccentric E being mounted loosely upon said 45 crank shaft and traveling with it when the key e', on the shaft is seated either against the shoulder e', constituting the right hand end of the key way e, or against the shoulder e'', forming the left hand end of said key 50 way, as the case may be, and as hereinafter more fully described.

The upper end of the eccentric rod F, is 55 pivotally connected to the reciprocating slide G, which travels in the groove g, formed in the bracket a⁴, which is integral with the casing A, the slide being held in the groove g, by a plate H, which also encloses and confines the mechanism by which the time of sparking is varied with relation 60 to the position of the piston P. This vari-

able sparking mechanism is interposed between the reciprocating slide G and a controller L, and may be of any form and construction that may be found expedient or practicable; it being shown herein simply 70 as an essential device or element used in conjunction with my special form of eccentric E,—the essential feature in this connection being the use of means for varying the engagement of the electrical contact surfaces by which the sparking is effected.

Thus in the drawings I have shown by way of illustration variable sparking mechanism adapted to "make and break" contact 75 sparking, as well as to "jump" or secondary sparking, the result being essentially the same in either case, and the specific construction of the variable sparking mechanism forming no part of the present invention.

The controller L, is preferably although not necessarily made in the form of a hand lever secured rigidly to the outer end of a short shaft l, which is mounted in a bearing h, in the plate H.

In the case of the "make and break" variable sparking mechanism shown in Figs. 1 to 12 of the drawings inclusive, the inner end of the shaft l, has rigidly secured to it a cam l', against the peripheral surface of 95 which rests a "tripper" or wiper I, pivotally supported upon the upper end of the reciprocating slide G, and held in engagement with said cam l', by a spring i, interposed between the short arm i', of said wiper I, and the opposed side of the slide G, as will be seen by reference to Figs. 4 and 5. J is a plug inserted through an aperture a⁵ (Figs. 2 and 6) in the casing A, to which it is secured by bolts j, j. Passing through but insulated from the plug J is the stationary positive terminal j', Fig. 8. This terminal j', is connected by the wire j'', with the knife switch j³, which in turn is connected with the spark coil or intensifier j⁴, 100 interposed in the circuit between said switch j³, and the battery j⁵, as illustrated symbolically in Fig. 1. The battery j⁵, is connected by the circuit wire j⁶, with the casing of the motor. Passing through the plug J but not insulated therefrom, so that it is in electrical contact with the casing A, see Fig. 11, is the rock shaft K. To the inner end of this rock shaft K, and formed integral therewith, is the arm k, which constitutes the negative terminal of the electrical circuit, and also acts as the contact maker and breaker (see Figs. 7 and 8). Upon the outer end of the rock shaft K is loosely mounted the radial arm k', which rests normally against a stop k², (integral with said shaft K) by reason of the action of a coiled spring k³, one extremity of which engages said radial arm k', Fig. 8, while its other extremity passes through the outer end of 110

120

125

130

135

the rock shaft K. In operation the upward stroke of the "tripper" or wiper I, raises the radial arm k', from the stop k², the motion being taken up and neutralized 5 by the spring k³, acting through the shaft K, holding the circuit breaker k, in contact with the terminal j'. Upon the release of the radial arm k', by the rocking wiper I, the spring k³, returns the radial arm k', to the stop k², with a quick, forceful movement, the impact of which drives the contact breaker k, acting through the rock shaft K, suddenly from the stationary terminal j', thereby effectively breaking the circuit and 10 causing the formation of a spark between the terminals by which the charge of hydro-carbon above the piston is exploded. It is obvious that the position of the cam l', with relation to the rocking wiper I will determine 15 the length of time of contact between its upper end and the radial arm k', so that by adjusting said cam l', by means of the controller L the timing of the spark may be varied with relation to the upward stroke 20 of the slide G.

Where a "jump" spark is desired instead of a "make and break" spark, the variable sparking mechanism shown in Figs. 13 to 30 inclusive may be substituted for that above described, or any other suitable variable sparking mechanism adapted to the purpose may be used. In the "jump" spark arrangement shown the upper end of the reciprocating slide G, is formed with a contact g', for engagement with a contact i², mounted on the plate I', but insulated therefrom by any suitable means, as by the washers i³, i⁴. The contact i², preferably consists of a metallic ball held in position by 35 resilient pressure, as by means of a spring i⁴ as shown in detail in Fig. 16. The upper portion of the plate I', is formed with a vertical longitudinal slot i⁵, through which passes the shaft l, to which the controller L 40 is rigidly secured. To the inner end of the shaft l, is secured the disk i⁶, or an equivalent lateral arm carrying a pin or stud i⁷, which rests in the transverse slot i⁸, in said plate I'. By this means the plate I', may 45 be raised or lowered with relation to the reciprocating slide G, so as to advance or retard the engagement of the contacts i², and g'. The contact i² is connected by the wire j', with the knife switch j³, which in turn 50 is connected to the primary wire of the Ruhmkorf coil j⁴, the other end of said primary wire being connected with the battery j⁵, which is grounded at j⁶. The secondary wire is grounded at j⁷, the other end 55 of said secondary wire connecting with the circuit closer j⁸, which in turn is connected with the jump spark plug J' of well known construction, the pole J²² being insulated from the pole J²³, which is in electric contact 60 with the engine casing A.

Whichever form of variable sparking mechanism is used the parts are so arranged and timed with relation to each other that if the controller L (if it be a lever as shown in the drawings) were in a vertical position the sparking would occur at the upper end of the stroke. If the controller L be turned to the right the sparking will be retarded or take place after the piston has commenced its receding movement, and vice 70 versa, if the controller is turned to the left of said central position, the sparking will take place in advance of the completion of the upward stroke of the piston.

Presuming that the normal direction of 80 rotation of the crank shaft is from left to right as is ordinarily the case, in effecting the preliminary starting of the engine the controlling lever L is set to the right and the fly wheel rotated to the right by hand. 85 This insures the engagement of the key c', with the right hand shoulder or seat e', of the eccentric, and the sparking is retarded. This retarded sparking is however resorted to only in effecting such preliminary starting 90 in order to overcome all danger of back action which might injure the person handling the fly-wheel, or for the purpose of reducing the speed of the engine, for any cause while running, since retarded sparking 95 impairs the effectiveness of the explosion of the charge for reasons well known. After the engine is started the spark may be advanced a suitable point by moving the controller lever L to the left, beyond the 100 center more or less, as may be found most expedient.

When it is desired to reverse the motion of the engine which ordinarily is only an incidental feature of its use, I open the 105 knife switch j³, thereby cutting out the sparking mechanism temporarily. When the momentum of the engine has been reduced to a degree insufficient to overcome the force of the explosion in an advanced 110 position, (the key c' being still in engagement with the right hand shoulder e', of the eccentric) I close the switch j³, the controller lever L having been previously turned farther to the left to give an increased lead of spark. Under these conditions the explosion will occur by an advanced spark on such stroke, according to the lead given to the controller L. As a result of the pressure 115 the generated gases 120 against the upper end of the piston the reduced momentum of the fly-wheel is overcome, the piston retarded and then forced downward before the completion of its upward stroke, and hence before the crank has 125 reached the upper dead center. This reversal of motion carries the key c', away from the right hand shoulder e', of the eccentric E and into contact with the left hand shoulder e², of the latter, thereby 130

versing the conditions heretofore described so that the next charge will be fired on a retarded spark, whereupon the spark may be advanced as desired by moving lever L to the right, and so on continuously until it is desired to restore the motor to its normal direction of rotation, in which case the sparking mechanism is again cut out until the momentum is reduced sufficiently to admit of the reversal of motion by the explosion of a single charge of hydro-carbon as just described, the eccentric E in both cases adjusting itself automatically to the change so as to actuate the sparking mechanism in like conditions in either case. By this means it will be seen that without the use or interposition of special or auxiliary mechanism of any kind and by the simple expedient of forming the sparker eccentric E, with a concentric seat slot e, admitting of a play or lost motion of say 90° between the two seats e' and e'' , or 45° on either side of the radial center of the crank shaft with which the key e' , coincides, I am enabled not only to readily reverse the motion of the engine but also to regulate and control its operation in either direction with equal facility and under like and parallel conditions; I thus attain a two way motor of simple and cheap structure which may be operated by unskilled labor, and by the use of which reversing gear and extraneous appliances or devices of any kind are or may be dispensed with. At the same time I am enabled to more effectually regulate and control the action of the engine irrespective of the direction of rotation of the crank shaft, a feature of practical importance especially as related to marine motors or others in which a reversal of motion or variation of speed is essential.

It is to be understood that while I have herein shown and described the eccentric E as formed with an eccentric seat slot having a play of 90° by way of illustration I do not limit myself in this respect, since any suitable degree of play or lost motion may be afforded without departing from the spirit and intent of my invention in this respect; neither do I restrict myself to a key e' , coinciding in position with the radial center of the crank.

What I claim as my invention and desire to secure by Letters Patent is;

1. In a hydro-carbon motor of the two-cycle character designated, the combination with variable sparking mechanism having means for advancing or retarding the spark at will by which the sparking may be effected during either the advance or recession of the piston, an eccentric and intermediate connections for operating said variable sparking mechanism, said eccentric being mounted loosely on the crank shaft and being formed with key seats, with a free key

space between the seats and a key upon said crank shaft between the said key seats on the eccentric, all so arranged that the operation may be reversed by merely opening and closing the circuit for the purpose described. 70

2. In a hydro-carbon motor of the two-cycle character designated, the combination with variable sparking mechanism having means for advancing or retarding the spark at will by which the sparking may be effected during either the advance or recession of the piston, an eccentric, and intermediate connections for operating said variable sparking mechanism, said eccentric being mounted loosely on the crank shaft and being formed with key seats 90° apart or approximately so, with a free key space between them, and a key upon said crank shaft between the said key seats on the eccentric, said key coinciding in position with the radial center of the crank, all so arranged that with the spark advanced on one stroke the operation may be reversed by merely opening and closing the circuit, for the purpose described. 80

3. In a two-cycle hydro-carbon motor of the character designated, the combination with variable sparking mechanism having means for advancing or retarding the spark at will by means of which the sparking may be effected during either the advance or recession of the piston, a crank shaft, an eccentric and intermediate connections for operating said variable sparking mechanism, said eccentric being mounted loosely upon said shaft of the engine and being formed with key seats with a free key space between them, and a key upon said shaft between the said key seats upon the eccentric, all so arranged that with the spark advanced on one stroke the operation may be reversed by merely opening and closing the circuit, for the purpose described. 95

4. In a hydro-carbon motor of the two-cycle character designated, the combination with variable sparking mechanism having a movable member to operate contacts and means to advance or retard the action of said member at will by means of which the sparking may be effected during either the advance or recession of the piston, a crank shaft, an eccentric and intermediate connections for operating said member of said variable sparking mechanism, said eccentric being mounted loosely upon said shaft of the engine and being formed with key seats 90° apart, or approximately so, with a free key space between them, and a key upon said shaft between the said key seats upon the eccentric, said key being timed in position to coincide with the radial center of the crank driven by the piston, all so arranged that with the spark advanced on one stroke the operation may be reversed by 130. 100

merely opening and closing the circuit, for the purpose described.

5. In a two-cycle hydro-carbon motor of the character designated, the combination of a crank shaft sparking mechanism having means for controlling the time of the spark at will so arranged that the time of making or breaking of contact may be varied through 90° of the rotation of the crank shaft and 10 an eccentric mounted loosely upon the said crank shaft with a key seat wide enough to admit of lost motion of 30° or 45° on either side of a key upon the crank shaft, and said key being placed to coincide with 15 the radial center of the crank, all so arranged that with the spark advanced on one stroke the operation may be reversed by merely opening and closing the circuit, for the purpose described.
- 20 6. In a hydro-carbon motor of the two-cycle character designated, the combination with variable sparking mechanism having a reciprocative member to make and break the circuit, and a controller to alter the time 25 of such make and break at will, by which the sparking may be effected either during the advance or recession of the piston, a reciprocating slide G connected with and arranged to actuate the said member of said 30 variable sparking mechanism, an eccentric rod, pivotally connected with said slide G, and connecting it with an eccentric E, said eccentric E, formed with a concentric slot e, and key seats e', e'', and a key e', on the 35 crank shaft C, said key being placed to coincide with the radial center of the crank c, all so arranged that with the spark advanced on one stroke the operation may be reversed by merely opening and closing the 40 circuit, for the purpose described.

7. In a two-cycle hydro carbon motor, the combination of a reciprocative member, an igniter comprising make and break contacts, an arm connected with the movable contact to be engaged by said member, and means to shift the operative position of said member with respect to said arm, with an eccentric loosely mounted upon the crank shaft, connections between the eccentric and said member, and means for causing the eccentric to travel behind the radial center of the crank in either direction of rotation of the latter, all so arranged that with the spark advanced on one stroke the operation may be reversed by merely opening and closing the circuit.

8. In a two-cycle hydro carbon motor, the combination of a reciprocative member, make and break contacts, an arm connected with one of said contacts, means to suddenly actuate the movable contact when the arm is released from said member, a cam to shift the position of said member with respect to said arm, and means to operate said cam, with an eccentric loosely mounted upon the crank shaft, and connections between the eccentric and said member, said eccentric having key seats with a free key space between the seats, and a key upon the crank shaft between said key seats for causing the eccentric to follow behind the radial center of the crank in either direction of rotation of the latter, all so arranged that the operation may be reversed by merely opening and closing the circuit.
